UNITED STATES PATENT OFFICE

GEORGE C. TEWKSURY, OF BRIDGEPORT, CONNECTICUT, ASSIGNOR TO
OLIVER C. SMITH, OF SAME PLACE.

DESIGN FOR A DIAL-PLATE FOR REGISTERING APPARATUS.

SPECIFICATION forming part of Design No. 20,005, dated July 8, 1890.

Application filed May 16, 1890. Serial No. 352,094. Term of patent 7 years.

To all whom it may concern:

Be it known that I, GEORGE C. TEWKSURY, a citizen of the United States, residing at Bridgeport, in the county of Fairfield and

5 State of Connecticut, have invented and produced a new and original Design for Dial-Plates for Registering Devices; and I do hereby declare the following to be a full, clear, and exact description of the invention, such as will 10 enable others skilled in the art to which it app- pertains to make and use the same.

The essential features of my design are a series of vertical parallel panels A and concentric slots B, leading from the upper end of 15 said panels and ending within the field of the dial C, as shown in the drawing, the whole

being shown upon a surface which is bounded by a circular outline in conventional representation of a circular fan.

D is the fan-handle.

The dial has the pattern O, of circular form, within its upper field.

I claim—

20 The design for a dial-plate for a registering device, as shown.

25 In testimony whereof I affix my signature in presence of two witnesses.

GEO. C. TEWKSURY.
